R. L. WILCOX.

THREADING DIE.

APPLICATION FILED AUG. 23, 1915.

Patented July 10, 1917.

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

THREADING-DIE.

1,232,876.

Specification of Letters Patent. Patented July 10, 1917.

Application filed August 23, 1915. Serial No. 46,941.

To all whom it may concern:

Be it known that I, RICHARD LESTER WILCOX, a citizen of the United States, residing at Waterbury, in the county of New Haven 5 and State of Connecticut, have invented a certain new and Improved Threading-Die, of which the following is a specification, reference being had therein to the accompanying drawings.

10 My invention relates to new and improved dies for threading screws, bolts and similar articles.

15 It is the object of my invention, among other things, to produce pointed screws with dies, that may be economically constructed, be interchangeable, reversible, and attachable to any one of the many forms of thread rolling machines now in common use.

20 To these, and other ends, my invention 20 consists in the dies for pointing and threading screws, bolts and similar articles, constructed substantially as hereinafter described and as illustrated in the accompanying drawing, wherein,—

25 Figure 1 is a plan view of a pair of thread rolling dies constructed in accordance with my invention and occupying the relative positions assumed by them at the commencement of the thread rolling operation;

30 Fig. 2 is a perspective view of one of the dies;

Fig. 3 is a face view thereof with the knife plate removed;

Fig. 4 is an end view thereof;

35 Fig. 5 is a face view of the knife plate;

Fig. 6 is an edge view thereof;

Fig. 7 is an end view thereof; and

40 Figs. 8, 9, 10, 11 and 12 are enlarged sectional views of the die and knife plate,

45 taken respectively upon lines A, B, C, D and E of Fig. 3, with the blank shown in connection therewith.

Heretofore it has been the practice to produce a gimlet point screw by pointing 45 the blank in a lathe, shaving machine or similar mechanism, and then forming the thread thereon. With my improved method the blanks are pointed and threaded at one and the same operation.

50 In the drawings, the numeral 1 designates the fixed die and 2 the movable die, both being of substantially the same shape, differing only in their length, the fixed die

being longer than the movable die, and the former being provided with the guide notch 55 9. These dies are secured in the usual way in any one of the many common forms of thread rolling machines. Each die has an angular recess 3 in one side thereof and upon the adjacent faces are the knives 4, 60 which are parallel with the side of the dies and terminate at their inner ends at the edge of the recess 3. The front face of each of the dies is provided with the usual thread rolling grooves 5 which extend from the 65 outer edges of the dies to and upon one side of the knives 4 (see Fig. 2).

Secured within the recess 3 by a screw 6 is the knife plate 7, having the knives 8 at opposite ends and upon opposite sides thereof. The knife plate 7 is so shaped and designed that its position within the recess 3 may be reversed end for end, if desired.

The dies 1 and 2 are arranged relatively 75 so that each of the knives 8 upon the knife plate 7 is in the same line as one of the knives 4 upon the opposite die, and the ends thereof have substantial contact with each other.

In practice, the blank, designated herein 80 by the numeral 10, is placed between the dies in the usual manner, its starting position being substantially shown in Fig. 8, and its alinement being determined by the guide notch 9. As the movable die 1 advances parallel with the face of the fixed die 2, the thread is rolled upon the shank of the blank and the knives 4 and 8 force their edges into the blank until a small portion of the end of the blank, designated herein 90 by the numeral 11, is separated from the blank and drops from between the dies into a receptacle conveniently arranged to receive it and leaving the end of the blank pointed, substantially as shown in Fig. 11. 95

The successive steps required to produce this result are shown in Figs. 9, 10 and 11, and the further movement of the movable die advances the blank so that the tapered or gimlet point end is threaded by the 100 grooves 5, which are formed in the outer curved face of the knives 4, as above described, thus completing the screw.

In the pointing and threading of screws by dies substantially as herein described, 105 only the minimum amount of material is

wasted, and one complete operation, necessary in the old practice of pointing and threading screws, is eliminated.

In minor details my new and improved 5 dies may be varied from that herein shown and I do not therefore limit myself to a die constructed exactly as shown and described except as the scope of the claims requires.

Having described my invention, what I 10 claim as new and desire to secure by Letters Patent, is:—

1. A die for rolling threads, having a recess in one face thereof; a knife in the same face adjacent to said recess; grooves 15 in said face which extend into one side of said knife; and a knife plate within said recess and having a knife thereon which forms an extension of the knife on said die.

2. A thread rolling die, having a recess 20 in the face thereof, knives upon said face adjacent to said recess and shorter than the die, thread rolling grooves in said face adjacent to said recess and extending into one side of each of said knives, in combination 25 with a knife plate within said recess, having knives thereon that form an extension to the knives on said die.

3. A thread rolling die, having a recess in the face thereof, knives upon said face adjacent to said recess and shorter than the die, thread rolling grooves in said face adjacent to said recess and extending into one side of each of said knives, in combination 30 with a reversible knife plate within said recess, having knives thereon that form an extension to the knives on said die.

4. A die for rolling threads, having a knife on one face thereof, grooves in said face which extend into one side of said 40 knife; and a separable knife connected with said die and forming an extension of the knife on said die.

5. A thread rolling die, having a knife upon one face thereof, a portion of which 45 is integral and a portion separable, and grooves in said knife face.

6. A thread rolling die, having a knife upon one face thereof, a portion of which is integral and a portion separable, and 50 grooves in said knife face and one portion of said knife.

7. A thread rolling die, having a recess in the face thereof, knives upon said face adjacent to said recess and shorter than the 55 die, thread rolling grooves in said face adjacent to said recess and extending into one side of each of said knives, in combination with a knife plate within said recess, having knives thereon that form an extension to

the knives on said die; and means for reversibly securing said knife plate to said die.

8. A die for rolling threads, having a recess in one face thereof; a knife in the same face adjacent to said recess; grooves in said 65 face which extend into one side of said knife; and a knife plate within said recess and having a knife thereon which forms an extension of the knife on said die, said knife plate being constructed with a knife upon 70 one edge thereof shorter than the length of the edge.

9. A die for rolling threads, having a recess in one face thereof; a knife in the same face adjacent to said recess; grooves in 75 said face which extend into one side of said knife; and a knife plate within said recess and having a knife thereon which forms an extension of the knife on said die, said knife plate being constructed with a knife upon 80 each edge thereof shorter than the length of the edge, said knives being substantially parallel with each other but not with the edges adjacent thereto.

10. A die for rolling threads, having a 85 recess in one face thereof; a knife in the same face adjacent to said recess; grooves in said face which extend into one side of said knife; and a knife plate within said recess and having a knife thereon which 90 forms an extension of the knife on said die, said knife plate being constructed with a knife upon one edge thereof shorter than the length of the edge but not parallel therewith.

11. A thread rolling die, having a recess in one face thereof, the side wall of which is at an angle to the side of the die, a knife in said face adjacent to said recess, grooves in said face which extend into one side of said knife, and a plate within said recess, having a knife thereon which forms an extension of the knife upon said die.

12. A die for rolling threads, having a recess in one face thereof; a knife in the same 105 face adjacent to said recess; grooves in said face which extend into one side of said knife; and a knife plate within said recess having a knife thereon which forms an extension of the knife on said die, said knife plate being constructed with a knife upon 110 one edge thereof shorter than the length of the edge and the top face of said plate adjacent to the knife edge, being beveled toward the outer ends thereof.

In testimony whereof I have hereunto affixed my signature.

RICHARD LESTER WILCOX.
